(75) Inventor: **William P. Apps**, Alpharetta, GA (US)

(73) Assignee: **Rehrig Pacific Company**, Los Angeles, CA (US)

(**) Term: **14 Years**

(21) Appl. No.: **29/170,756**

(22) Filed: **Nov. 11, 2002**

Related U.S. Application Data

(63) Continuation of application No. 29/140,364, filed on Apr. 16, 2001, now Pat. No. Des. 465,417.

OTHER PUBLICATIONS

Exhibit 1: Four photos of a prior art case of Rehrig Pacific Company, Model No. PLBC-8-2L-PET-QD (1984).

Exhibit 2: Two photos of a prior art case of Rehrig Pacific Company for 3 liter PET bottles (1990).

Exhibit 3: Two photos of a prior art case of D.W. Plastics (Date unknown).

Exhibit 4: Two photos of a prior art case of International Container Systems, Inc. for 3 liter PET bottles (Date unknown).

Primary Examiner—Dominic Simone

(57) **CLAIM**

The ornamental design for handle portion for stackable low depth crate, as shown and described.

DESCRIPTION

FIG. 1 is a perspective view of handle portion for stackable low depth crate showing my new design;

FIG. 2 is a top plan view thereof;

FIG. 3 is a bottom plan view thereof;

FIG. 4 is a front side elevational view thereof; and,

FIG. 5 is a right side elevational view thereof.

The broken lines shown are for environmental purposes only and are not part of the claimed design.

1 Claim, 5 Drawing Sheets
